UNITED STATES PATENT OFFICE.

GEORGE R. WYMAN, OF EAST WALPOLE, MASSACHUSETTS, ASSIGNOR TO
F. W. BIRD & SON, OF EAST WALPOLE, MASSACHUSETTS, A FIRM.

BOX-MACHINE.

SPECIFICATION forming part of Letters Patent No. 731,729, dated June 28, 1903.

Application filed May 5, 1902. Serial No. 105,898. (No model.)

To all whom it may concern:

Be it known that I, GEORGE R. WYMAN, a citizen of the United States, residing at East Walpole, in the county of Norfolk and State of Massachusetts, have invented certain new and useful Improvements in Box-Machines, of which the following is a specification, reference being had therein to the accompanying drawings.

10 This invention has reference to improvements in box-machines, and relates particularly to that class of box-machines whereby the open ends of boxes or cartons are closed and the closures secured.

15 The object of the invention is to mechanically close certain end portions of a box or carton and to secure such portions in the closed position.

20 Another object of the invention is to so construct a machine of this character that the mechanism for turning down the cemented portion shall be controlled by the cement or glue applying means.

25 Another object of the invention is to improve the cement or glue applying means.

Another object of the invention is to provide an ejecting device adapted to eject boxes of different sizes.

30 The main object of the invention is to generally improve box-machines of the character herein described whereby the closing of the ends of the boxes or cartons and the ejecting of the boxes from the machine are effected.

35 The invention consists in the construction of the glue-applying mechanism and in its association with its co-operating parts.

The invention also consists in the movable flap-support and in its combination with the glue-applying mechanism.

40 The invention also consists in the former, its carrying mechanism, and the means for exerting pressure on the closed end of the box.

45 The invention also consists in the peculiar construction of the former or anvil carrying mechanism, the ejecting device, and the means for actuating the ejector.

The invention also consists in such other novel features of construction and combination of parts as shall hereinafter be more fully described, and pointed out in the claims.

Figure 1 represents a front elevation of the

improved machine. Fig. 2 represents an end view of the same. Fig. 3 represents a plan view of the machine, particularly illustrating the controlling relation between the frame of 55 the glue-applying mechanism and the folder-plate. Fig. 4 represents a view of the form-carrier removed from the machine and disclosing the ejector, a closed box being in position on the form. Fig. 5 represents a perspective view of a box one end of which is designed to be closed by this machine. Fig. 6 represents a side view of portions of the form and the folder-plate with an open-end box in position to be operated on. 60

65 Similar characters of reference designate corresponding parts throughout.

This machine is designed for use in closing one of the open ends of a box or carton similar to that shown in Fig. 5, having the flaps 70 *a* and *b* *c*, by closing the flaps down onto a form or anvil, applying glue or cement to the flaps during such closing, and subjecting the end of the box thus formed to pressure, and finally ejecting the box from the machine. 75

In the drawings, 5 and 6 represent the side or end frames of the machine, connected at their upper ends by the hood or plate 7 of substantial construction and designed to resist a considerable pressure. Journaled in 80 bearings in these frames 5 and 6 and in the bracket 8 is the main drive-shaft 9, and on this shaft is journaled the sleeve 10, adapted for driving connection therewith by means of any usual form of clutch mechanism furnished with a stop, as 12. On this sleeve 10 are secured the drive-pulleys 13, 14, and 15, and on the shaft 9 are fixed the pressure-cam 16, the ejector-cam 17, and the carrier-actuator cam 18, this latter having dwells 19 and 20 located with registering relation to the active portions of the cams 16 and 17, an acting portion 21, and a return 22. 85

At the lower portion of the frames 5 and 6 is journaled the rock-shaft 23, having the 95 treadle 24 and the locking-arm 25, adapted to engage the stop 12 and hold the friction mechanism out of engagement with the shaft 9 until said stop is released by the depression of the treadle. Also journaled in the frames 100 5 and 6 is the shaft 26, having the arm 27, the antifriction-bearing at the free end of which

rides on the edge of the pressure-cam 16. Pivotedly mounted on studs extending from this arm 26 is the carrier-arm 28, one side of the yoke 29 of which has the depending member 30, in which the stud-shaft 31 is secured, this stud-shaft working through the opening 5' of the frame 5 and being pivotally engaged in a perforation of the arm 32, the slot in this arm 32 working over that portion of the shaft 10 which is between the outer face of the frame 5 and the cam 18 and the slotted end of this arm 32 having a projecting pin 33, carrying an antifriction-sleeve which works against the edge of the cam 18. To the yoke 29 of the carrier-arm 28 are secured drawing-springs 34, the other ends of which are secured to the respective frames 5 and 6.

The carrier-arm 28 (more fully illustrated in Fig. 4 of the drawings) has the channel 35, 20 in which is freely movable the block 36, carrying the ejector-rod 37, having at its upper end the spur 38, the downward movement of the block 36 being limited by the stop 39. At the sides of the carrier-arm are secured the 25 steps 40, 40, which may be adjustable on their bolts, and on the free end of this carrier-arm is the form or anvil 41, centrally perforated to permit of the working of the ejector-rod therethrough and removably secured to the 30 end of the arm 28 by means of the screw 42 or other suitable securing device. The form 41 is preferably of a size and shape corresponding generally to the inner cross-sectional shape and size of the box to be supported thereby and is removable for the substitution of forms of other shapes and sizes to substantially correspond to the like dimensions of boxes of various sizes and shapes without change in the ejector device, this 35 40 ejector being designed to act on boxes of any shapes or sizes capable of passing through the machine. The steps 40 are adjusted with reference to the length of the box, or, if desired, the adjustment between these steps 45 and the surface plane of the former may be effected by increasing or diminishing the thickness of the form 41.

The arm 43 has a slotted portion which works over the shaft 9 between the frame 6 50 and the cam 14 and is furnished with the pin 44, which is engaged within the cam-lip of said cam. At its upper end this arm 43 is pivoted to the crank-lever 45 of the sleeve 46, journaled on the shaft 47, which is fixed 55 in the frames 5 and 6, a stop 48 being provided on said sleeve for limiting the rocking of the sleeve by contact with the frame 6 and this sleeve being furnished with the ejector-finger 49, the free end of which is designed 60 for engagement with the block 36 of the carrier-arm when said block is brought to a suitable position.

The flap-support and turning-down plate 50 has arms which are pivoted in the frames 5 and 6 and has the diagonally-extending finger 51, the stop 52, fixed on the frame 5, being intended to limit the depression of this

plate 50 and to act as a support therefor. Other means for movably supporting and sustaining this plate 50 may, however, be used. 70

From the frame 6 extends the bracket 53, on which the glue or cement reservoir 54 is supported, and in this reservoir is rotatably mounted the supply-roll 55, the shaft of which is provided with a pulley 56, which is driven 75 by the belt 57 from the pulley 15. Also rotatable in the reservoir 54 is the distributing-roll 58, driven by means of the gears 59 and 60, which distributes the glue over the surface of the supply-roll 55, the speed at which 80 this roll 58 is driven being determined by the relative proportion of the gears 59 and 60. Below the reservoir 54 are bearings in which is journaled the shaft 61, having at one end the bevel-gear 62 and at the other end the 85 pulley 63, driven by the belt 64 from the pulley 14. Also projecting from the frame 6 is the bracket-plate 65, having the upwardly-extending collar 66 and the pivoted clutch-latch support 67, and below this plate 65 is 90 the bearing 68, also secured to the frame 6. In the collar 66 and the bearing 68 is journaled the vertical shaft 69, to the upper end of which is secured the frame 70, carrying the shaft 71, on which the glue-roll sections 95 72 and 73 are independently rotatable. On this shaft above the collar 66 is fixed the cam-plate 74, having downwardly-curving ends, and above the bearing 68 is freely rotatable on said shaft the clutch mechanism 75 of any 100 well-known construction, designed to be engaged by the key or latch 76 of the shaft 69 when this key or latch is released by the swinging outward of the pivoted latch-support 67, this clutch mechanism having the 105 bevel-gear 77, which meshes with the gear 62 of the shaft 61, and the pivoted latch-support being controlled by the thumb-lever 78, pivoted on an extension of the bearing 68 and connected with the latch-support. 110

A box or carton similar to that shown in Fig. 5 of the drawings having been placed on the form 41, the flaps *a a* are turned down by the operator and rest on the surface of the form, as shown in Fig. 4. The operator now 115 presses the thumb-piece 78, thus moving the support 67 to permit the engagement of the key 76 with the clutch 75, which causes the rotation of shaft 69. The glue-roll frame 70 is swung on its axis, and the roll-sections 72 120 and 73, either or both, are brought over the outer surface of the flap *b*, turning the same down onto the flaps *a a* and applying glue to such outer surface. During this swinging of the glue-roll frame the cam 74 has worked 125 under the pin 51 of the plate 50 and this pin and its plate have been permitted to drop approximately to the level of the flap *b* or to the plane in which the lower surface of the glue-roll sections move. The glue-roll sections, 130 continuing their swinging movement, pass over the inner surface of the flap *c* and press it down onto the plate 50. As the application of glue to the flap *c* is completed the lower

end of the cam 74 engages the pin 51 of the plate 50, and as the higher portions of the cam ride under this pin the plate 50 is elevated to the position shown in Fig. 2 as the glue-roll 55 comes to a rest on the supply-roll 55. Approximately at the time when the circuit of the glue-roll has been completed the operator depresses the lever 24, thus throwing the clutch mechanism into engagement to connect the sleeve 10 with the drive-shaft 9. This shaft being thus caused to rotate, the cam 18 permits the drawing of the arm 32 in one direction by the drawing action of the springs 34 34 on the carrier-arm 28 until the form 41, with the box, is brought under the cap 7, the initial portion of this swinging movement of the carrier-arm bringing the outer surface of the flap c against the edge of the plate 50 and causing the turning down of said flap by the plate until the glued surface of the flap is in approximate contact with the outer surface of the flap b. When the form 41 has been brought under the cap 7, the bearing of the pin 33 is against the pressure-dwell 19 of the cam 18. The cam 16 has now rotated to a position where its acting portion works against the roller-bearing of the yoke 27 and forces the same upward, thrusting the end of the box against the under side of the cap 7 and compressing said end between the form and the cap to set the glued portions, the cam 16 then relieving the pressure and allowing the carrier to drop. As the cam 16 allows the dropping of the carrier the portion 21 of the cam 18 is brought opposite the bearing of the pin 33 and allows the springs 34 to draw the carrier to the position shown in dotted lines in Fig. 2 of the drawings, and here another dwell 20 is brought opposite said pin 33. At the approach of the carrier-arm to this last position the engageable end of the ejector-arm 49 has engaged the ejector-block 36 and the cam 14 has been rotated, so that as the carrier reaches said position the cam portion 14' acts on the pin 44 of the arm 43 and through the connected mechanism actuates the arm 49 to sharply swing the same, and thus impel the ejector-rod 37 upward along its guideway and force the box from the form 41, the cam 14 then permitting the arm 43 and its related mechanism to return to place, while the cam 18 acts against the bearing of the pin 33 to force the same back against the action of the springs 34 and swinging the carrier-arm to the starting position.

By the use of the spur 38 in the end of the ejector-rod the box is held from accidental displacement.

Having thus described my invention, I claim as new and desire to secure by Letters Patent—

1. A box-machine, comprising a carrier-arm pivotally supported to swing and having a channel, an ejector movable in said channel, and an ejector-actuating mechanism normally separated from said ejector.

2. A box-machine comprising a carrier-arm

mounted for swinging and endwise movement, and an abutment toward which said arm may move at times.

70

3. A box-machine comprising a carrier-arm, a lever on which the arm is pivoted, means for moving the lever, and fixed means for resisting the thrust of said arm at times.

4. A box-machine comprising a carrier-arm 75 pivotally mounted, a fixed member under which the free end of the arm may be swung, and mechanism for moving the carrier-arm endwise toward such fixed member.

5. A box-machine comprising a carrier-arm 80 having a yoke at its lower portion and a member depending below said yoke, a pivoted lever to which said yoke is pivoted, cam-actuated means for operating the lever and the dependent member independently, and an 85 abutment toward which the actuation of the lever moves the carrier-arm.

6. A box-machine of this nature comprising a pivoted carrier, an ejecting device carried thereby, means for swinging said carrier, and an ejector-actuating mechanism 90 engageable with the ejecting device only when the carrier has been swung to its limit of movement from the starting-point.

7. A box-machine of this nature comprising a carrier mounted for swinging and longitudinal movement, and a glue-applying mechanism adapted to work above the end 95 of said carrier, when the carrier is retracted and depressed.

100

8. A box-machine of this nature, comprising a pivoted carrier adapted to support an open-end box having flaps to be turned down, and a support for the outermost flap movably mounted in the path of the carrier adapted to be raised to permit of the passage thereunder of the carrier and to turn down said outermost flap.

105

9. A box-machine, comprising a flap-support and turning plate movably mounted, and a gluing mechanism in controlling relation to such plate.

110

10. A box-machine, comprising a flap-support and turning plate movably mounted, a gluing mechanism adapted to swing over said plate, and connections between the plate and the gluing mechanism, whereby the plate is depressed for the passage of the glue mechanism and elevated after said passage.

115

11. A box-machine, comprising a carrier-arm pivotally mounted, a form at the upper end of the carrier, a combined flap-support and turning plate pivotally mounted adjacent to said form, a gluing mechanism adapted to move over the top of said form and said plate, and controlling connections between said plate and the gluing mechanism, whereby said plate is positioned to permit the passage of the gluing mechanism, and is thereafter raised.

120

125

12. A box-machine of this nature, comprising a carrier pivotally mounted and furnished with a form, a flap-supporting plate, movably mounted in the path of movement of said

130

form, a glue-applying device movable over said form toward said plate, and means for elevating the plate after the passage of the glue-applying mechanism.

5 13. A box-machine of this nature, comprising the shaft 69 journaled in bearings, and furnished with the cam 74 and the frame 70, the glue-rolls 72 and 73 rotatably mounted in said frame, and a flap-supporting plate movably mounted and having a member bearing on said cam 74.

14. A box-machine of the nature described, comprising a stationary compression member, a carrier adapted to be swung under and moved toward said member, and a flap-supporting plate movably mounted in the path of said carrier.

15. A box-machine of this nature, comprising side frames, a lifting-lever pivoted in the side frames, a carrier pivoted on the lifting-lever, an ejecting device movably mounted on the carrier and having an engageable portion, an ejector-actuating mechanism movably mounted at a distance from the initial position of the carrier and adapted to intercept and engage the engageable portion of the ejecting device, and means for operating said actuating means.

16. A box-machine of this nature comprising side frames having a cap, a lifting-lever pivotally mounted therein, a carrier pivotally mounted on the lever, means for swinging

the carrier to a dwell under the cap, then continuing the swinging thereof to a dwell at the end of its path and returning it to its initial position without dwell, and means for elevating the free end of the lifting-lever during the period of dwell.

17. A box-machine of this nature, comprising a carrier mounted for swinging and longitudinal movement, means for swinging the carrier and for interrupting said swing intermediate its throw and at the end of its throw, means for moving the carrier longitudinally during said intermediate interruption, and ejecting mechanism operative during the dwell of the carrier at the end of its throw.

18. A box-machine of this nature, comprising the frames 5 and 6, the shaft 47 secured therein, the sleeve 46 journaled on the shaft 5c and having the arm 49, means for rocking the sleeve to give an impulse to the arm, and a carrier movably mounted and furnished with an ejector which is adapted to be intercepted by the end of said arm and to be actuated by 55 the movement thereof, as and for the purpose described.

In testimony whereof I affix my signature in presence of two witnesses.

GEORGE R. WYMAN.
